UNITED STATES PATENT OFFICE.

WILLIAM BURTON WESCOTT, OF WELLESLEY, MASSACHUSETTS, ASSIGNOR, BY MESNE ASSIGNMENTS, TO TECHNICOLOR MOTION PICTURE CORPORATION, OF BOSTON, MASSACHUSETTS, A CORPORATION OF MAINE.

METHOD OF PRINTING CINEMATOGRAPHIC FILMS.

Application filed November 18, 1921. Serial No. 515,583.

To all whom it may concern:

Be it known that I, WILLIAM BURTON WESCOTT, a citizen of the United States of America, and resident of Wellesley, in the county of Norfolk and State of Massachusetts, have invented new and useful Improvements in Methods of Printing Cinematographic Films, of which the following is a specification.

10 This invention relates to cinematography and more particularly to cinematographic printing of the multiplex type, that is, of the type adapted to print a plurality of series of complemental images.

15 In the projection of motion pictures it has been found desirable in changing from one scene to another, instead of making the change abruptly, gradually to merge the following scene into the preceding scene so

20 that as one scene fades out the other scene is gradually substituted, this process being known as a "dissolving" process. In the production of ordinary black and white pictures this dissolving phenomenon is usually effected by varying the size of the dia-

25 phragm opening in the camera while exposing the negatives from which the positives exhibiting the dissolving phenomenon are produced. That is, while exposing the latter portion of one series of views the dia-

30 phragm is gradually closed and while exposing the first portion of the succeeding series of views the diaphragm is gradually opened. Then in printing the positives the

35 two series of views are overlapped by printing the first portion of the second series over the latter portion of the first series.

While this method is fairly satisfactory for black and white cinematography it involves a number of disadvantages which I purpose to overcome. In the former process the rate of decrease and increase in the intensity in the latter and former portions of the overlapped series of views is finally determined in the camera so that, if incorrect, it cannot be corrected either in printing or projecting and all pictures produced from the negatives will be defective. While a skilled photographer can usually determine the proper time to begin to reduce the intensity of the first series, he frequently makes mistakes, and unless highly skilled an operator is usually too much occupied with other matters properly to attend to

this detail. Moreover, it is frequently desirable to eliminate the last or the first portion of a series of views and in the old process this involves cutting away the diminuendo or crescendo portions of the film and sacrificing the dissolving phenomenon.

However, a more serious objection to the described dissolving process is met with in the production of color pictures by multiplex films, that is, by films having two or more series of complemental images, as for example one series recording the red aspect of the object field and a corresponding or complemental series recording the green aspect of the object field. As fully described in the patent to Daniel F. Comstock, No. 1,283,087 the contrast gradients of the images in the respective complemental series, which are produced by the components of light of different dominant hues, are different, the images formed by the red component of light having a steeper contrast gradient than the images formed by the green component, in the two-color process for example. If the two contrast gradients coincide at the normal degree of exposure they diverge as they extend downwardly from the point of intersection, and as the intensity of the images of the respective complemental series are decreased their contrast gradients differ more and more. Moreover, in the ordinary panchromatic negative film employed in motion picture work, and particularly in the film used in color work, the emulsion is exceedingly sensitive and the straight portion of the contrast gradients are correspondingly short. Thus, if the complemental pictures of normal intensity have the proper relative color values, in the old dissolving process where the dissolving effect is introduced in the original negatives by varying the diaphragm opening in the camera, the degree of exposure is varied either upwardly or downwardly along the contrast gradients; and, owing to the fact that the contrast gradients for the respective complemental series of images, for example the red series and the green series, diverge and have only short straight portions, the pictures of diminished intensity will not have proper relative color values, particularly in the region below the straight portions of the contrast gradients. The result is that if the complemental pictures of normal intensity have the

proper relative color values the diminuendo or crescendo pictures will not have the proper relative color values but will be too green in the shadows.

6 The principal object of the present invention is to overcome the above and other difficulties and to obtain a more convenient and adaptable method and means for effecting the dissolving phenomenon either in black 10 and white or color cinematography. To this end the invention, in its preferred form involves no variation of the intensity of the end portions of the original negative film as in the old process, but on the contrary I 15 preferably produce the diminuendo and crescendo effects in printing the positive film from the negative films. The succeeding series of views are preferably overlapped upon the positive film as in the old process 20 but unlike the old process the intensity of the printing light is gradually diminished in printing the latter portion of the first series and the intensity of the light is gradually increased in printing the overlapping portion 25 of the succeeding series, it being understood that the diminuendo and crescendo portions of the two series which are overlapped are preferably substantially equal in length. In projecting the two series of images the positive film is run through the projector continuously and upon reaching the end of the 30 first series of views the first series gradually merges into the second series.

35 By my new method the camera operator, who has many details to occupy his attention and who is frequently required to operate under difficult conditions, is relieved of attending to the dissolving effect. In printing the positives from the negatives the provision for the dissolving phenomenon can be 40 more carefully and accurately made; and, in the event that the first positives do not display the desired effect, the printing can be so varied as to provide the desired effect in 45 subsequent positives. Moreover, should portions of the negative films be undesirable they may be eliminated without destroying the dissolving effect inasmuch as the provision for the effect is first made in the positives. 50

However, I believe the most unique and desirable use of the present invention to be in the production of multiplex films, whether the complemental image be disposed side by 55 side as in the additive processes or in superposition as in the subtractive processes. The particular utility of the invention for color work is due in part to the particular stage of the process of exposing, printing and projecting, in producing motion pictures, in 60 which I introduce the dissolving effect, and in part to the adaptability of my improved method of producing the described diminuendo and crescendo effects. In applying 65 my invention to the subtractive process of

color cinematography the respective series of complemental positives may be printed either independently at different times or they may be printed concomitantly as disclosed in my prior application Serial No. 70 149,791, filed February 28, 1917. Moreover, either white light, similarly colored light or, as in prior application Serial No. 112,378 above referred to, light of different colors 75 may be employed to print the respective complemental series. In applying the invention to the additive process of color cinematography the respective series of positives may be printed in any desired manner, as for example in the manner disclosed in the patent 80 to Daniel F. Comstock No. 1,390,983 granted September 20, 1921. In either event the difficulties of the old dissolving method are overcome as will now be described.

Unlike the panchromatic negative films, 85 which have exceedingly sensitive emulsions and correspondingly short straight portions in their contrast gradients, the ordinary positive films are relatively very slow and have contrast gradients whose straight portions are long. The straight portions of the gradients for each of the complemental series 90 of positive images can be made coincident or at least parallel by suitably adjusting the light values in the printer and the degrees of development in developing the respective series of positives, or by suitably choosing the color values of the printing light. Thus owing to the relatively great length of the 95 straight portions of the positive gradients and owing to the fact that the slope of the gradients of the respective complemental series may be made substantially equal, unbalancing of the color values of the positive series due to the relatively great decrease of 100 the intensity of the printing light, in producing the diminuendo and crescendo portions of the positive films, is avoided, the decrease of intensity not extending much if any below the straight portions of the contrast gradients. Thus, in introducing the 105 dissolving effect in the printing process instead of in the exposing process the relative color values of the complemental images projected upon the screen are not unbalanced during the transition from one scene to another. The advantages resulting from my new method of introducing the dissolving effect, wherein the shutter opening is gradually varied in size, will be apparent from the 110 detailed description of the mechanism for the purpose as hereinafter set forth.

Suitable apparatus for practicing the method therein claimed is shown in Patent 125 No. 1,417,005 granted May 23, 1922 on my copending application Serial No. 176,652, filed June 25, 1917, of which this is a continuation in part.

I claim:

1. In the art of cinematography the meth-

- od of dissolving one scene into another scene, comprising gradually decreasing the intensity of the light in printing the last of the series of views of the first scene, gradually increasing the intensity of the light in printing the first of the series of views of the second series, and projecting the said first and last of the respective series of views in overlapped relationship so that the first 5 series gradually merges into the second scene.
2. In the art of cinematography the method of producing a transparency having overlapping series of views, the overlapping portions of which gradually decrease in intensity in opposite directions, comprising printing upon a sensitive strip one series of views, gradually decreasing the intensity of the light throughout the latter 15 portion of the series, and printing upon the sensitive strip another series of views, gradually increasing the intensity of the light throughout the first position of the latter series, the two series being so printed upon 20 the strip that the said latter portion and the said first portion of the respective series overlap.
3. In the art of cinematography the method of dissolving one scene into another scene, comprising gradually decreasing the shutter opening in printing the last of the series 30 of views of the first scene, gradually increasing the shutter opening in printing the first of the series of views in the second scene, and projecting the said first and last of the respective series of views in overlapped relationship so that the first scene gradually merges into the second scene.
4. In the art of cinematography the method of producing a transparency having overlapping series of views, the overlapping portions of which gradually decrease in intensity in opposite directions, comprising printing upon a sensitive strip one series of 35 views, gradually decreasing the shutter opening throughout the latter portion of the series, and printing upon the sensitive strip another series of views, gradually increasing the shutter opening throughout the 40 first portion of the latter series, the two series being so printed upon the strip that the said latter portion and the said first portion of the respective series overlap.
5. In the art of color cinematography employing a plurality of series of images of the object field the respective series of which correspond to different dominant hues, the method of dissolving one scene into another scene, comprising gradually decreasing the intensity of the light in printing the last of the plurality of series of negatives of the first scene, gradually increasing the intensity of the light in printing the first of the plurality of series of negatives 55 of the second scene, and projecting in overlapped relationship the portions of the series of positives corresponding to the said first and last of the series of negatives, so that the first scene gradually merges into the second scene without undue variation in color 70 values.
6. In the art of color cinematography employing a plurality of intercalated series of images of the object field, the respective series of which correspond to different dominant hues, the method of producing a transparency having the series of images of one scene overlapping with the series of images of another scene, the overlapping portions of which gradually decrease in intensity in 75 opposite directions, comprising printing upon a sensitive strip the plurality of intercalated series of images of the one scene, gradually decreasing the intensity of the light for each series throughout the latter portion of the scene, and, in printing upon the sensitive strip the plurality of intercalated series of images of the other scene gradually increasing the intensity of the light for each series throughout the first portion of the scene, the two scenes being so printed that the said latter portion and the said first portion of the respective scenes overlap, whereby, in projecting, the first 80 scene may be caused gradually to merge into the second scene without undue variation in color values.
7. A process of making a "dissolve" between two successive scenes of a moving picture film, which comprises printing from the last few photographs of that portion of a moving picture film which corresponds to a given scene, such photographs being of approximately equal intensity, a succession of prints upon a moving picture film, such succession of prints being of successively lower intensity, such successively lower intensity being produced by gradually reducing the light admitted to such printing operation, also printing upon the said portion of such second-mentioned film from the first few photographs of that portion of a moving picture film which corresponds to the commencement of the succeeding scene, such photographs also being of approximately 90 equal intensity, a succession of prints of successively greater intensity, such successively greater intensity being produced by gradually increasing the light admitted to such printing operation, the margins of the two sets of prints being substantially coincident, and thereafter developing the said second-mentioned film.
8. A process of making a positive picture film having a "dissolve" between two successive scenes, which comprises exposing the negative film as if no "dissolve" effect were to be made, developing the negative, thereafter printing from the latter portion of that section of a resulting film of substan- 100
- 105
- 110
- 115
- 120
- 125
- 130

tially standard intensity which corresponds to a given scene of the finished picture, a succession of prints upon a given portion of a film, such succession of prints being of 5 gradually and successively decreasing intensity, such successively lower intensity being produced by gradually reducing the light admitted to such printing operation, also printing upon same portion of last-mentioned film, from the first portion of that section of a resulting film of substantially standard intensity which corresponds to the next succeeding scene of the picture, a succession of prints, such last-mentioned succession 10 of prints being of gradually and successively increasing intensity, such successively greater intensity being produced by gradually increasing the light admitted to such printing operation and thereafter 15 developing the printed film.

9. A process of making a positive motion picture film having a "dissolve" between two successive scenes, which comprises exposing the negative film for such two scenes, as if 20 no fade effects were to be made, thereafter printing from the later portion of that section of the negative film which corresponds to a given scene of the finished picture, a succession of prints upon a given portion 25 of a positive film, such succession of prints being of gradually and successively decreasing intensity, the first of such succession of prints being of approximately standard intensity, and the last of such succession of prints being so faint as to be substantially negligible, also printing upon 30 such portion of positive film, from the first portion of that section of the negative film which corresponds to the next succeeding 35 scene of the finished picture, a succession of prints, such last-mentioned succession of prints being of gradually and successively increasing intensity, starting with a print which is so light as to be substantially negligible and finishing with a print which is of 40 substantially standard intensity, by varying the amount of light admitted to both of said printing operations, and thereafter developing the printed positive.

45 10. In the production of "dissolve" effects in printing a moving picture film, the steps 50

of printing from the portion of a developed film corresponding to the latter portion of that section of a film which corresponds to a given scene of the finished picture, a succession of prints upon a given portion of a film, such succession of prints being of successively decreasing intensity, by successively decreasing the amount of light reaching the developed film during such printing operation, also printing upon same portion of such second-mentioned film, from the first portion of that section of a developed film which corresponds to the next succeeding scene of the finished picture, a succession 55 of prints, such last mentioned succession of prints being of successively increasing intensity, by successively increasing the amount of light reaching the developed film during such second printing operation, 60 such two printing operations being performed in any desired order.

11. The process of producing a "dissolve" effect from one scene into another scene, by reducing in a gradual way the light reaching the film during the printing operation, by reducing the light a given fraction of the whole in each picture from full printing density of light to such an amount of light as will produce substantially no effect, and also "fading in" by increasing in a gradual way the light reaching the film during the printing operation from such an amount of light as will produce substantially no effect to substantially full printing intensity of light, thus dissolving one scene into the next.

12. A process of producing a fade, which comprises the step, in the printing operation, in which light passes through the successive frames of a developed moving picture film onto a sensitized film, of successively and gradually changing the amount of light supplied to said developed film, between two limits, one of said limits representing such an amount of light as will produce substantially standard intensity printing, and the other of said limits representing such an amount of light as will produce such a small amount of printing as to be negligible.

Signed by me at Boston, Massachusetts, 100 this 14th day of Nov. 1921.

WILLIAM BURTON WESCOTT.
